UNITED STATES PATENT OFFICE

2,488,057

TRAIN STOP MECHANISM

George G. Ensign, Robert R. Lawson, Earl H. Schaefer, and Wenzel M. Wochos, Jr., Elgin, Ill., assignors to Elgin National Watch Company, Elgin, Ill., a corporation of Illinois

Application June 18, 1945, Serial No. 600,040

2 Claims. (Cl. 58—7)

1

It is often desirable to provide stop mechanisms to prevent motion of clockwork devices. For example, a spring driven chronometer may be provided with a removable escapement assembly; and means are desired to prevent rundown of the spring, with possible damage due to the abnormal motion, when the escapement assembly is removed.

A feature of this invention is the provision of a stop mechanism with means for moving a stop latch into and out of blocking position with relation to the clock train.

Another feature of this invention is the provision of a stop mechanism having a spring-actuated detent which tends normally to block the train, but which is moved during the operation of assembly of the parts so that the train is released for its proper motion.

Another feature is the provision of an assembly including a clockwork having a removable escapement which is secured in position by a screw, a stop mechanism having a spring-actuated detent which tends normally to block the train, and in which the operation of engaging the screw moves the stop mechanism to ineffective position.

An illustrative form of practice of the invention is shown on the accompanying drawing, in which:

Figure 1 is a side elevation of a chronometer, with part of a pillar broken away to show stop mechanism elements.

Figure 2 is a sectional view, on an axial section through the pillar, with the stop latch in disengaged position, substantially on line 2—2 of Figure 1.

Figure 3 is a view corresponding to Figure 2, but with the stop latch in engaged position.

The stop mechanism is illustrated as employed with a chronometer which has the pillar plate 10, the train plate 11, and the connecting and spacing pillars 12, 13 held by the screws 14. The usual parts inclusive of main spring, gear train, hands, and the like are provided, but for clarity of the drawing this train is shown only as the fourth wheel 15. Such structures are well-known, and no invention is claimed therein.

A removable escapement assembly is shown, which may be of the form shown and claimed in the copending application Serial No. 633,946, filed December 10, 1945, to which reference is made for details of assembly and construction. For purposes of the instant invention, it is sufficient that this assembly has a balance cock 18 which is secured to the train plate by using balance cock

2

mounting screws 19 of which one is shown as threaded into the underlying pillar 13. When such screws 19 are removed, the balance cock 18 may be lifted away, carrying with it the escapement and thereby releasing the train from the normal timing controls. It is customary to provide locating dowels 20, or closely fitted surfaces at the edges of the balance cock, whereby to assure accuracy of positioning.

10 According to the illustrated form, the pillar 13 has an axial slot 25 through which extends an arm 26 of the train stop latch, this arm having an upturned outer end 27 for engaging in an aperture 28, of which one or more are provided in the fourth wheel 15. Within the pillar 13, the latch has a knee 29 and a shank portion 30, the latter extending upwardly into the path of axial seating movement of the balance cock mounting screw 19.

20 A coil spring 33 is provided within the pillar 13, and engages between the bottom of the knee 29 and the inner end of the securing screw 14 (Figures 2 and 3). By removing the screw 14, the spring 33 can be withdrawn.

25 In operation, when all parts are assembled, the stop mechanism is in the position of Figure 2, with the end 27 free of the fourth wheel 15. The chronometer runs and keeps time. If, for any reason, it is desired to remove the escapement 30 assembly, the balance cock mounting screw 19 is turned, so that it rises in the pillar 13. Under the urge of the spring 33, the latch follows the screw 19, until its end 27 engages the fourth wheel 15, or enters an aperture 28 thereof. The latch is loosely fitted in the pillar 13, so that it can rock in its own plane, i. e. in a radial plane through the axis of the pillar. When the screw 19 has been raised a distance sufficient to permit the balance cock 18 to be moved for rotation

40 about the axis of this screw, as for example by separation of the dowel 20 from its reception cavity, the latch has attained a position for stop engagement. If the fourth wheel 15 has not presented an aperture 28 for the end 27, a partial rotation of the fourth wheel effects this presentation; and thus the latch attains the position of Figure 3, in which it blocks the fourth wheel and stops the train. The screw 19 can then be completely removed, without further event, and the balance cock 18 separated from the train plate without releasing the train to run down.

When the parts are to be assembled again, the balance cock 18 is placed accurately in position 55 and the escapement therewith is meshed with

the train; the screw 19 is seated and rotated. During the downward axial movement of the screw 19, it encounters the end of the shank portion 30, and depresses the latch, until ultimately the parts are in the position of Figure 2, with the fourth wheel 15 free to turn.

Thus, in the illustrated preferred form, the train is under control at all times, being either held to timed motion by the escapement, or held in stopped position by the latch: and no special manual operation or care need be observed to accomplish these results.

It will be noted that the pillar 13 can perform its normal function of spacing the plates 10, 11; and that the screws 14, 19 assure these plates, as well as the balance cock 18, against separation when the parts have been assembled.

It is obvious that the invention is not limited to the specific illustrated form, but may be employed in many ways within the scope of the appended claims.

We claim:

1. A stop mechanism for a clockwork having plates separated by a pillar, a clock train having an apertured fourth wheel, a demountable balance cock, and means connectable with the clock train to control the same, which comprises a latch axially movable in and guided by the pillar for movement in a plane parallel to the axis of said wheel, and said latch having an outwardly projecting arm having an upturned end engageable in an aperture of the fourth wheel of the train, a spring in the pillar effective for urging the latch into blocking engagement with said fourth wheel, and a balance cock mounting screw for securing the balance cock in position, said screw being threadable into the pillar and effective at its lower end as the screw approaches final securing position to engage and move said latch axially along the pillar and out of blocking engagement with the fourth wheel.

2. A stop mechanism for a clock-work having plates separated by a pillar, a clock train mounted on said plates and having an apertured wheel, a demountable balance cock, and a screw for securing the balance cock in position; which comprises a latch having a portion guided in said pillar, said pillar being hollow and threaded internally at its end adjacent the position of the balance cock for receiving said screw, said pillar also having an axial slot leading from its central hollow to the exterior, said latch having a portion extending through said axial slot and guided thereby for axial movement along the slot and having an outer end portion which in one position engages in an aperture of said wheel to block the same against rotation, and a spring in the pillar and cooperative with the latch for urging the same into such blocking engagement, said securing screw being effective while being threaded into the pillar for moving said latch axially to disengage its said end portion from said wheel.
